UNITED STATES PATENT OFFICE.

PHILIP A. JACKSON, OF ATLANTA, GEORGIA, ASSIGNOR TO THE EGRY REGISTER COMPANY, OF DAYTON, OHIO, A CORPORATION OF OHIO.

AUTOMATIC REGISTER.

Application filed November 14, 1923. Serial No. 674,736.

This invention relates to an automatic register that is designed more especially as an improvement upon the structure disclosed in my copending application for an automatic register filed February 16, 1922 Serial No. 537,079.

The general object of the invention is to provide means whereby with one revolution of the operating handle webs of the desired 10 length may be fed, the feeding automatically interrupted and the webs automatically aligned ready for the next operation.

One of the objects of the invention is to provide simple and efficient means whereby 15 the bills or memorandums for the transaction of business will be automatically centered relative to each other so that the lines and spaces thereon will match prior to entries being made.

20 A further object is to provide means for automatically releasing the webs containing the bills or memorandums so that they can be shifted relative to each other by the alining or centering means.

25 Another object is to provide simple and efficient means for shifting the webs relative to the alining or centering means as soon as the webs are released, thereby cooperating with said alining means to bring the super- 30 posed webs in proper relation to each other.

Another object is to provide means whereby the mechanism can be varied for use in connection with bills or memorandums of different lengths.

35 With the foregoing and other objects in view which will appear as the description proceeds, the invention resides in the combination and arrangement of parts and in the details of construction hereinafter described 40 and claimed, it being understood that changes in the precise embodiment of the invention herein disclosed may be made within the scope of what is claimed without departing from the spirit of the invention.

45 In the accompanying drawings the preferred form of the invention has been shown.

In said drawings—

Figure 1 is a plan view of the register, partially broken away.

50 Fig. 2 is a side elevation of the complete register.

Fig. 3 is a section on line 3—3 of Fig. 1 and looking in the direction of the arrows.

55 Fig. 4 is a vertical sectional view on the line 4—4 of Fig. 3.

Fig. 5 is a plan view of one of the devices used for holding a web taut.

Fig. 6 is a detail perspective view of the webs of paper used in conjunction with my invention.

60 Referring to the drawings the register comprises a casing having a base 1 and end-walls 1^a, sidewalls 3 and a cover 3^a. The cover is cut away to provide access to a writing table 2 supported by the sidewalls 65 3 in any suitable manner. In the sidewalls 3 rearwardly of the writing table 2 are a plurality of recesses 4, the bottom walls of which are inclined downwardly and rearwardly, as shown in Figures 2 and 3. Rolls 70 6 carried by arms 5 pivoted in the sidewalls 3 rest on the bottom walls of the recesses 4 and are normally held by gravity against the back walls of the openings, for the purpose 75 hereinafter set forth.

The cover 3^a at its forward end is formed into an upwardly extending housing 7 to contain an upper feeding roller 8 having spindles 9 extending through elongated openings 10 in the sidewalls 3 and having 80 discs 16 on the ends thereof. A roller 12 co-acts with the roller 8 to feed the webs of paper and is secured to a shaft 11 adapted to be mounted in the sidewalls 3 below and directly in line with the spindles 9 of the 85 roller 8. Loosely mounted on the shaft 11 are cams 17 adapted once during each rotation thereof to engage the discs 16 and lift the roller 8 upwardly away from the roller 12 to release the webs positioned between 90 said rollers. Each cam 17 is secured to a gear 18 also loosely mounted on the shaft 11.

An operating shaft 19 is journaled in the side walls 3 and is provided with any suitable means, such as a crank arm 20, for rotating it. Secured to the end portions of this shaft 19 are gears 21 and said gears mesh with intermediate gears 22 that engage the gears 18. Thus when shaft 19 is rotated motion will be transmitted therefrom to the cams 17. The gears 21, 22 and 18 are of the same size.

100 Fixedly secured to the shaft 11 within the walls of the casing are gears 23 adapted to receive motion through gears 24 from gears 25 secured to the shaft 19. These gears constitute means for rotating the roll 12 for the purpose of feeding webs gripped between the rolls 8 and 12. By using a larger or smaller gear 25 the machine can 105 110

be caused to deliver longer or shorter bills.

Transverse shafts 26, 27, 28 and 29 are supported in the side walls 3 and the shafts 26, 27 and 28 carry web rolls 30 on which are printed the bills, memorandums or other blanks. The web 31 extending from the shaft 26 is preferably fastened over the rear roll 6 and thence over the writing table 2 from which it is extended between the gripping rolls 8 and 12. The web 32 extending from shaft 27 is extended over the middle roll 6 and between the writing table 2 and the upper web 31 and is also positioned between the feeding rolls. The third web 33 is extended over the remaining roll 6 and thence between the web 32 and the writing table 2 and between the gripping rolls. The other end portion of this web 33 is extended downwardly and secured to the shaft 29 so as to be rolled thereon. To the shaft 29 are secured gears 34 which are actuated from the main operating crank 20 through a suitable train of gearing comprising the gears 25, 24, 23, 35, 36 and 37, as shown in Fig. 3. Interposed between the record roll carried by the shaft 29 and the gear 34 are the usual friction devices composed of steel and fiber washers 38 and 39.

In order to provide the web 33 with sufficient slack to permit of the alignment of the several webs a stationary jaw in the form of a plate or block 43 is supported by the sidewalls 3 close to a portion of the web 33 between the feeding rollers and the shaft 29, and pivotally mounted adjacent this jaw 43 is a movable clamping member 44 having a rearwardly extending arm 45. A rotatable cam 46 having a peripheral recess 47 is secured to the gear 24. A spring 48 is secured at one end to the side of the casing by a stud 49 and to the arm 45 at the other end, as shown. This spring is under tension and serves to exert an upward pull on the arm 45, thereby causing the clamping member 44 to turn about its pivot 50 and hold the paper between it and the jaw 43 when the recessed portion 47 of the cam 46 comes opposite the arm 45. The operation of the machine is so timed that this holding of the paper will take place immediately after the feeding rollers have been separated and the pins have dropped into the perforations of the paper.

In order to exert tension on the webs of paper 31, 32 and 33 at the point where they leave the supply rolls, I provide frames 51 pivoted to the sidewalls 3 and carrying rollers 52 which bear downwardly on the webs and serve to check the unwinding of the paper upon ceasing to turn the operating crank.

Each of the webs 31, 32 and 33 is provided, between the printed bills or memorandum forms, with openings 39^a designed to register when the superposed printed

forms properly register one above the other.

Brackets 40 are provided at the sides of the casing within the housing 7 and pivotally mounted in and extending between these brackets is a plate 41 from which are extended pins 42 each having a vertical front portion against which the webs are aligned and a tapered rear portion to permit the pins to ride out of the perforations in the paper. These pins are designed to bear by gravity upon the upper web while it is moving thereunder.

In using this apparatus the webs, after receiving the data written thereon upon the writing table 2 are fed by rotating the crank 20. This will cause the gears 25, 24 and 23 to rotate roll 12. As this roll and the roll 8 engage the webs said webs will be actuated so as to project from the machine the filled out portions of the webs. The openings between the used portions of the web and the next adjoining blank will pass under the pins 42 and immediately thereafter the cams 17 will engage the discs 16 and force roll 8 upwardly, thus relieving the webs from the feeding action of the rolls 8 and 12. At the same time the recessed portion of the cam will come opposite the arm and the spring will move the member 44 about its pivot to clamp the paper between said member and the stationary jaw. During the forward feeding of the webs as before explained the rolls 6 will be pulled upwardly along the inclined lower walls of the opening 4 but as soon as the webs are released from the gripping action of the rolls 8 and 12 these rolls 6 will act as weights and will gravitate along the lower inclined walls of the openings 4, at the same time pulling on the webs. Consequently after the openings 39 in the web have been brought into position under the pins 42 and these teeth have dropped into the openings, the weight of the rolls 6 act to align the webs because the mechanism is so timed that when the pins drop into the openings, cams 17 release the webs and the rolls 6 draw the webs back and align them by bringing the front edges of the openings against the pins.

The filled in portion of the web can be torn off in the usual way and the apparatus is ready for a repetition of the operation that has been described. It will be noted that while the blanks are being torn off and also while being filled in above the writing table 2, the webs are held at the front by the rolls 8 and 12 and at the back by rolls 6. By beveling the pins 42 the webs, when moved forward will lift the pins from the openings.

Especial attention is directed to the fact that under all conditions one rotation of the crank 20 produces but one rotation of gears 18, and cams 17 by which the gripper rolls are separated, whereas the roll 12 can be caused to rotate one or more times during

each rotation of the crank, this being dependent on the length of bills to be issued. The variation of the rotation of roll 12 is effected by changing the gears used for transmitting motion thereto.

5 What is claimed is:—

1. In an autographic register for feeding a plurality of paper sheets having spaced series of perforations, feeding rollers, means 10 to actuate said rollers to feed said sheets, means to separate said rollers to interrupt the feeding of said sheets, means to automatically enter perforations in said sheets to align them and to automatically ride out 15 of said perforations on the re-feeding of the paper, and common operating means for said feeding and separating means, the several steps in the operation consisting of feeding the desired length of sheets and re-aligning 20 the sheets ready for the next operation being automatically performed by one revolution of the operating means.

2. In an autographic register for feeding a plurality of paper sheets having spaced 25 series of perforations, feeding rollers, means to actuate said rollers to feed said sheets, means to separate said rollers to interrupt the feeding of said sheets, means to automatically enter the perforations in said 30 sheets to align them and to automatically ride out of said perforations on the re-feeding of the paper, means to automatically grip one of the sheets after it has passed through the feeding rollers while said rollers are separated, means to exert a backward pull on said sheets when the feeding 35 rollers are operated and to draw the paper taut on the writing table when the rollers are in feeding position, common operating 40 means for said roller feeding means, roller separating means and sheet gripping means, whereby upon one revolution of said operating means the desired length of sheet is fed, the feeding rollers are separated and the 45 sheets re-aligned for another operation.

3. In an autographic register for feeding a plurality of paper sheets having spaced series of perforations, feeding rollers, gearing 50 to actuate said rollers to feed said sheets, a cam to separate said rollers to interrupt the feeding of said sheets, gearing for actuating said cam, gravity actuated pins adapted to automatically enter perforations in said sheets to align them and to automatically ride out of said perforations on the 55 re-feeding of said paper, and a common operating handle for both sets of gearing, whereby upon one revolution of said handle

the desired lengths of sheets are fed, the feeding rollers are separated and the sheets 60 re-aligned for another operation.

4. In an autographic register for feeding a plurality of paper sheets having spaced series of perforations, feeding rollers, gearing to actuate said rollers to feed said sheets, 65 a cam to separate said rollers to interrupt the feeding of said sheets, gearing for actuating said cam, gravity actuated pins adapted to automatically enter perforations in said sheets to align them and to automatically ride out of said perforations on the re-feeding of the sheets, cam actuated means to automatically grip one of the sheets after it has passed through the feeding rollers and during the separation of said 70 rollers, rollers carried by pivotally mounted frames adapted to exert a backward pull on said sheets to align them against the aligning pin when the feeding rollers are separated and to draw the paper taut on the 75 writing table when the rollers are in feeding position, and a common operating handle for both sets of gearing, whereby upon one revolution of said handle the desired lengths of sheets are fed, the feeding rollers 80 are separated and the sheets re-aligned for another operation.

5. In an autographic register for feeding a plurality of paper sheets having spaced series of perforations, a writing table, feeding rollers, means to actuate said feeding rollers to feed said sheets, means to separate said rollers to interrupt the feeding of said sheets, means located adjacent said feeding rollers above the writing table to automatically enter perforations in said sheets to align them and to automatically ride out of said perforations, means located in the forward part of said register to grip one of said sheets during the separation of said feeding 90 rollers, and means located in the rear part of said register for exerting a rearward pull on said sheets to draw them against the aligning means during the separation of the feeding rollers and to keep the paper taut on the writing table, and a common operating means for said feeding and separating means, the several steps in the operation of feeding the desired lengths of sheets and re-aligning the sheets ready for the next operation being automatically performed upon 95 one revolution of the operating means.

In testimony that I claim the foregoing as my own, I have hereto affixed my signature.

PHILIP A. JACKSON.
